STARTING MECHANISM FOR COMPRESSOR

Erich A. Wachsmuth, Michigan City, Ind., assignor to Joy Manufacturing Company, Pittsburgh, Pa., a corporation of Pennsylvania

Application August 9, 1956, Serial No. 603,156

11 Claims. (Cl. 60—16)

This invention relates to free-piston, internal combustion engine-driven compressors, and more particularly to apparatus for starting the initial cycle of operation of such machines.

The present invention is particularly adapted for but not restricted to utility with free-piston compressors of the type employing two opposed-piston systems arranged and connected in counterstroke relation to each other, i.e., with the pistons of one system traveling in the opposite direction to the corresponding pistons of the other system. It does have special utility with diesel or other high compression motors.

In devices of this general character, manual starting of the internal combustion engine is nearly impossible either since the various motor pistons are not connected to a common crankshaft by rotation of which the pistons can be moved or because of the pressures encountered. In order to start operation of these compressors, various means are utilized to move the opposed engine pistons of one system rapidly away from each other in order to move the opposed engine pistons of the other system rapidly together thereby compressing the fuel mixture in the latter system and effecting ignition of the mixture in that system. An effective means for rapidly moving the motor pistons apart on a starting stroke has been the use of a specially manufactured cartridge shell fired in the engine combustion chamber and which causes the engine-pistons to be moved apart. Other means for initiating this stroke, and of the more complicated variety, is the use of compressed air which may be injected, at a sufficiently high pressure, into the compressor system to force the associated pistons together.

Generally, the use of one of the foregoing methods of starting precludes the use of the other so that in the event the supply of cartridge shells has depleted, or the cartridges on hand have become damp or otherwise unusable, the compressor must remain idle until the circumstances are altered. In some cases, especially where the compressor is located in a relatively remote place, the availability of a new supply of cartridges may be delayed, resulting in needless "down-time" of the compressor. Similarly, the use of compressed air for starting the work cycles of the compressor may be curtailed in the event the supply of compressed air has been depleted, or the complicated valve mechanism utilized therewith has become inoperative. Therefore it is the principal object of the present invention to provide an auxiliary starting mechanism for a free-piston compressor without interfering with the regular starting mechanism therefor and thus insure the ready availability of at least one starting mechanism for the compressor.

The present invention takes in one preferred embodiment, the form of a combustion chamber housing which may be suitably secured to the combustion chamber wall for communication with one of the engine cylinders of a free-piston compressor of the type utilizing two opposed piston systems. The combustion housing is adapted to receive a supply of combustible fuel-air mixture therein

2

and a suitable ignition means is provided for igniting the mixture within the housing. A series of pressure-sensitive valves are arranged within the housing for opening a normally closed valve permitting the expanding gases within the housing to enter the combustion chamber of the motor-compressor thereby effecting rapid separation of the engine pistons housed within the combustion chamber jacket. The amount of the fuel-air mixture that is allowed to be ignited in the combustion housing and the timing of the opening of the normally closed valve is such as to substantially duplicate the normal expansion stroke of the engine piston in that sufficient compression is attained between the engine pistons of the other engine cylinder for initiating normal operation of the compressor.

15 The combustion housing may be permanently fastened to the cylinder jacket and remain a part thereof without interfering with the primary starting mechanism of the compressor and be readily available in the event the primary device is inoperative. The present invention may, however, be detached from the cylinder jacket and stored away and be used only during emergencies, some of which have been discussed above. In the alternative, the present invention may be utilized as a primary starting device, as will be readily apparent.

Another object of the present invention is to provide an improved free-piston engine-compressor embodying improved means for starting the same, which means will effect complete and maximum stroke of the engine-pistons affected thereby for insuring perfect starting thereof.

30 Other objects and advantages of the invention will become apparent upon reading the following detailed description of the invention taken in conjunction with the accompanying drawings wherein:

Fig. 1 is a fragmentary diagrammatic plan view in 35 central longitudinal section through a twin motor-compressor in which the present invention may be embodied;

Fig. 2 is a view taken along the lines 2—2 of Fig. 1 and shows on an enlarged scale the starting mechanism and its relationship with the twin motor-compressor; and

40 Fig. 3 is an enlarged sectional view taken on lines 3—3 of Fig. 2.

Now referring first to Fig. 1, it will be noted that there is shown a motor-compressor comprising a twin-engine cylinder 10, only one of which is shown since this engine cylinder and the other engine cylinder (not shown) are identical, and a detailed description of the cylinder 10 will suffice. For a more detailed illustration of the motor-compressor mechanism illustrated in Fig. 1 reference can be had to my copending applications Serial No. 272,019, filed February 18, 1952, now Patent No. 2,775,398, issued December 25, 1956; Serial No. 285,472, filed May 1, 1952, now abandoned, of which application Serial No. 634,395 is a continuation, now matured into Patent No. 2,841,322, issued July 1, 1958; and Serial No. 297,745, filed July 8, 1952, now Patent No. 2,755,988, issued July 24, 1956.

The engine cylinder 10 has reciprocable in it in counter-stroke relation to each other pistons 12, 14 which control scavenging ports 16 and exhaust openings 18. As 60 described and illustrated in the above mentioned applications, the four engine pistons, only two of which are shown in Fig. 1, are formed as differential pistons and are coupled in pairs by double-armed rockers 20, 22, respectively, the first pair by the rocker 20 and the second 65 by the rocker 22, so that the outward, working strokes of the pistons associated with the cylinder 10 occur with and compel inward, compression strokes of corresponding pistons (not shown) on the other cylinder (not shown) and viceversa. The double-armed rockers 20, 22 are pivoted respectively by shafts 24, 26 on the compressor frame F and they have in fixed relation to them.

gear segments 28, 30 which swing in the same angular directions as their respective rockers. These segments, through their mutual engagement, prevent the piston systems from getting out of synchronism with each other.

The outer ends of the rockers 20, 22 are respectively provided with bearings 32, 34 surrounding pins 35, 36 which in turn are supported in box elements 38, 40, and the box elements are slidably arranged with respect to the several pistons. In this manner, each of the several pistons has a relatively loose and frictionless connection with its respective rocker arm.

A pair of compressor cylinders 42, 44 are arranged coaxially with each of the motor cylinders 10 and are open at their ends toward the motor cylinder but closed at their other ends by cylinder heads 46, 48. These cylinder heads carry and house the suction and discharge valves 50, 52. A receiver 54, suitably connected in communication with another receiver (not shown) which is associated with the other engine-compressor (not shown) is adapted to receive air that is compressed during the outward stroke of air compression pistons 55, 56 reciprocable in the cylinders 42, 44, respectively.

Any suitable fuel supply and injection system may be incorporated in the engine-compressor. However, a preferable system is disclosed and illustrated in the above mentioned application Serial No. 285,472. To provide for unloading of the compressor, as is conventional in machines of this type, suitable unloading devices, generally indicated by the reference numeral 58 are arranged within the compressor heads 46, 48. A preferred arrangement for unloading the compression cylinders 42, 44 and the fuel injection and supply means therefor is adequately disclosed and illustrated in the above mentioned application Serial No. 285,472. In view of the full discussion in that application there need be no extended discussion of the fuel injection and supply means and the unloading mechanism in the present application.

Referring now to Fig. 2 it will be noted that the combustion cylinder 10 is surrounded by a combustion lining 60 which is suitably mounted in the frame F. A bore 62 is formed in the frame F at the midpoint, longitudinally of the cylinder 10, and is adapted to mount a chamber structure 64 communicating with the mid-point of the motor cylinder bore, and having suitable firing mechanism (not shown) associated with it. A small cartridge, provided with a correctly measured powder charge, is inserted in the structure 64, and serves normally as the primary starting device for the motor-compressor system. It will be apparent that during a normal starting cycle, the powder charge is ignited, thereby forcing the pistons 12, 14 apart while compressing the air between the pistons in the other motor-compressors thereby causing an explosion of the fuel injected at the end of the compression stroke into the compressed air, trapped between the engine pistons and initiating normal operation of the machine.

It will be apparent during normal operation that each time the various engine pistons uncover their associated exhaust and scavenging ports which they control, exhaust and scavenging will be automatically effected, and, upon the compression stroke of the engine pistons, new charges of air will be compressed and upon fuel injection, new working strokes will be caused to take place, and running will be continued under the control of the apparatus, much of which is described in my application Serial No. 285,472, above referred to. The frame F is also bored at 66 for mounting a suitable injection nozzle 68 which is adapted to communicate with the cylinder 10 through a bore 70 formed in the lining 60.

Mounted below the frame F is a starting mechanism generally indicated by the reference numeral 72 which serves as an auxiliary source of expansive power for driving the pistons 12, 14 apart for a starting operation. The starting mechanism comprises a combustion housing 74 for a combustion space S, and is preferably of

cylindrical construction, having a nipple 76 formed integrally on an end wall thereof and in axial alignment therewith. The nipple 76 is threaded at the extreme end thereof for engagement in a tapped bore 78 formed in the cylinder lining 60. The shank portion of the nipple 76 is adapted to be positioned in a well 80 formed in the frame F, and suitable packing 82 and an O-ring 84 are provided to prevent the escape of gases from the cylinder 10, and water leakage respectively, as will be readily understood. The other end of the housing 74, remote from the nipple 76, is closed by a cylindrical base block 86 having a portion 88 of reduced diameter for partial insertion into the housing. A shoulder 90 is provided on the block 86 and is adapted to abut the end of the housing 74 and to serve as a retaining flange for a fitting 92 which is threadedly engageable with a threaded portion 94 formed on the housing. In this manner, the block 86 may be detached from the housing 74 for replacement and maintenance of the control mechanism to be described hereinafter.

The block 86 is centrally bored at 96 to form a cylindrical chamber 98 for a piston 100 having a protruding rod 102 extending axially therefrom. The rod 102 projects interiorly of the chamber 98, through an opening 104 and into the interior of the housing 74. Upon movement of the piston 100 upwardly, the rod 102 is adapted to abut the end of a valve stem 106 in axial alignment therewith, but is normally spaced a short distance from the end of the stem 106 by a light coil spring 107 held in compression between one wall of the chamber 98 and the top surface of the piston 100. The block 86 is counterbored at 108 concentrically of the chamber 98 for supporting a plug member 110 which serves to limit the outward movement, or downwardly, as viewed in Fig. 2, of the piston 100 under the bias of the spring 107. The plug member 110 is locked in position between a shoulder 112 formed in the block 86 and one wall surface 114 of a cover plate 116 secured to the end of the block 86 by any suitable means. A suitable passageway may be provided in the block 86 for venting the chamber 98 to atmosphere during the upward movement of the piston 100 as will be apparent.

A valve member 118 is provided on the other end of the stem 106 and is adapted to cooperate with a valve seat 120 formed on the inner surface of the nipple 76 for controlling communication between the cylinder 10 and space S defined by the housing 74. As shown in Figs. 2 and 3, the valve stem 106 is guided for axial movement by a spider frame 122 mounted in the nipple 76 and having a cylindrical bearing 124 for slidably receiving the stem 106. The legs 126 of the spider 122 are secured in the nipple 76 between an annular shoulder 128 formed interiorly thereof and a retaining washer 130 rigidly secured in an annular groove 132 formed in the end wall of the housing 74. It will be apparent that the spaces between the spider legs 126 will permit the flow of combustion gases from the housing 74 and through the nipple 76.

Lifting of the valve member 118 from its seat 120 is limited by the engagement of a lock washer 134 secured to the valve stem 106, and one side of the frame 122. A similar lockwasher 136 is secured to the valve stem 106 at a point intermediate the position of the washer 134 and the end of the stem adjacent the rod 102. A sleeve 138 and a spherical shaped collar 140 encircle the stem 106 between the washers 134 and 136 and are locked against axial movement with respect to the stem by the washer 136 and a shoulder 142 formed on the stem 106 adjacent the washer 134. As previously stated, the valve member 118 is normally biased upon its seat and to this end there is provided a coil spring 144 held in compression between the washer 130 and the annular flange 146 of a spring-retaining cup 148 which is encircled by the spring 144. The cup 148 is inverted and is provided with an

opening 150 in the bottom portion thereof and the latter is bounded by a circular edge for engaging the spherical surface of the collar 140. The diameter of the circular edge of the opening 150 is made slightly less than the outer diameter of the collar 140 thereby preventing the axial movement of the cup 148 in one direction but allowing limited rocking movement about the collar 140. Movement of the valve stem 106 in a direction to lift the valve member 118 from its seat 120 is opposed by the spring 144 since the cup 148 is anchored for movement with the stem 106 in this direction by the lock washer 136 and the elements 138, 140.

The block 86 is also provided with a chamber 152 for receiving a pressure actuated mechanism generally indicated by the reference numeral 154. The pressure actuated mechanism comprises a plunger 156 having a collar 158 secured thereto and intermediate the ends thereof. The upper portion 160 of the plunger 156, as viewed in Fig. 2, is adapted to slide in a bore 162 formed in the block 86 and connected between the chamber 152 and the interior of the housing 74, while the lower portion 164 of the plunger extends into the chamber 152. The collar 158 limits the upward travel of the plunger 156 by its engagement with an end wall 166 of the chamber 152. Projecting radially upwardly a short distance into the chamber 152 are a plurality of abutments 168 and these serve to support a guide spool 170 having an aperture formed centrally thereof for receiving and guiding the axial movement of the lower portion 164 of the plunger 156. A coil spring 172 encircles the lower portion 164 and is held in compression between the lower surface of the collar 158 and the upper surface of the guide spool 170. It will be apparent that the parts of the pressure actuated mechanism 154, so far described, are normally in the position shown in Fig. 2 under the bias of the spring 172.

Mounted on the cover plate 116, in any suitable manner, is a normally open micro-switch 174, preferably of the single-pole, single-throw type, having the usual terminals 176, 178 mounted thereon for connection in an ignition circuit to be described hereinafter. The switch 174 also includes an actuating rod 180 which when moved inwardly into the switch 174, or downwardly, as viewed in Fig. 2, will close the contacts (not shown) in the switch. The plunger 156, when moved a sufficient distance against the bias of the spring 172 serves to abut and move the rod 180 for closing the switch 174, and, as it will be obvious, the return movement of the plunger 156 will permit opening of the switch. Suitable vent passages may be formed in the block 86 or the cover plate 116 for allowing the egress and ingress of air to the chamber 152 during the raising and lowering of the collar 158.

The contacts 176, 178 are connected in a series circuit with a battery 182, the primary winding of a step-up transformer 184 and a suitable interrupter 186. The high voltage secondary winding of the transformer 184 is connected in series with a spark plug 188 threadedly secured in a tapped bore 190 formed in one wall of the combustion housing 74. It will be apparent that this circuit is of the usual type for internal combustion engine ignition purposes and any other suitable circuit may be utilized for causing sparking of the spark plug 188. It will also be apparent that the closing of the switch 174 by the actuation of the plunger 156 will suffice for supplying the necessary high voltage to the spark plug 188.

As previously stated, the valve member 118 is normally held in a closed position thus preventing communication between the chamber 10 and the combustion space S of the housing 74. In order to trigger the movement of the valve member 118, there is provided a pressure sensitive triggering mechanism generally indicated by the reference numeral 192. This mechanism is housed in an elongated chamber 194 formed in the block 86 and

communicable with the housing 74 through a bore 196, and includes a slide valve member 198 extending along the longitudinal axis of the chamber 194. The slide valve 198 is provided with a needle valve member 200 which is adapted to be projected partially into the bore 196 in one position of the valve member 198 for closing communication between the space S and the chamber 194, and to be moved out of the bore 196 to establish this communication in another position of the valve member 198. The slide valve member 198 is provided with three lands 202, 204, 206, spaced longitudinally thereof, for guiding movement of the valve member along the walls of the chamber 194. The land 204 also serves to close off or vent to the chamber 96 and the land 206 serves as a pressure area as will presently appear. A passageway 208 is formed diagonally through the land 202 for permitting the flow of gases, as will be described later, between the spaces on either side of the land 202 and a passageway 209 is formed diagonally through the land 204 for permitting the flow of gases from the space between the lands 202, 204 to a groove 210 which separates the land 204 from the land 206. The groove 210 is normally in communication with atmosphere through a passageway 212 formed in the block 86 when the valve member 198 is in a position wherein the needle portion 200 is projected in the bore 196. However, the groove 210 will be closed to atmosphere in the event the valve member 198 is lowered sufficiently for the land 204 to slide across and close off the passageway 212. A passageway 213 in the block 86 connects the chamber 96 with the chamber 194 and is in communication therewith for all positions of the lands 202, 204 of the slide valve member 198.

The end of the land 206 is centrally bored at 214 for receiving a thrust pin 216 which is adapted to be received in a depression formed in a retaining disc 218. A coil spring 220 is held in compression between the disc 218 and a suitable screw adjusting device 222 and serves to normally bias the valve member 198 into position wherein the passageway 212 is open to the groove 210 and consequently the space between the lands 202, 204, and the needle valve 200 is projected into the bore 196.

To complete the starting mechanism, the combustion space S is adapted to receive a mixture of fuel and air under pressure, and, to this end, one wall of the housing 74 is threadedly bored at 224 for accommodating a fitting 226 of a fuel supply line 228. Any suitable source of fuel-air mixture may be utilized but preferably one that is capable of supplying the mixture at a pressure upwards of 100 p.s.i. Such a source may include an air-pump having the discharge thereof connected to a suitable metering-mixing device, for mixing the fuel and the throughpassing air before entering the supply line 228. A check valve 230 is interposed between the supply and the housing 74 for preventing the flow of burned fuel mixture to the source of fuel supply, as will be apparent.

Operation

With the parts in their respective positions as shown in Fig. 2, the starting apparatus of the present invention is disposed for a starting operation. At this point it may be well to state the relative strengths of the various springs utilized in the present invention and the effect of their strengths upon their respective mechanisms. It is to be understood that the designated pressure requirements of this description have been arbitrarily chosen, and that it is the relationships between the elements described that account for the proper functioning of the present invention. It will be assumed that the normal compression pressure in the engine cylinder 10 during normal operation of the compressor is approximately 800 to 1000 p.s.i. and the peak combustion pressure under full load approximately 2000 p.s.i. The pressure to be developed in the space S may be considerably less than that pressure required for diesel action in the compressor,

however, in this instance, the amount of expanding gas in the space S, after ignition, must be relatively large. The size of the starting housing 74 is such that the mean pressure of the expanding gas developed therein times the piston displacement between the starting position thereof and the exhaust port openings equal the same amount of work as performed at the next following expansion stroke caused by the first diesel ignition.

The spring 220 for the pressure sensitive triggering mechanism 192 is preferably of a strength slightly exceeding 100 p.s.i., or of a strength to maintain its extended condition for all pressures of the fuel mixture before combustion thereof. On the other hand, the spring 172 for the pressure switch mechanism 154 is adapted when compressed to approximately 100 p.s.i. to effect closure of the switch 174. The spring 144 for the valve member 118 is relatively strong, being adapted to maintain seating of the valve member 118 when there is a pressure of approximately 500 p.s.i. resulting from combustion in the space S. This pressure is adapted to work upon the under surface of the valve member 118 and the force caused thereby is insufficient for lifting the valve member from its seat. However, as will presently appear, when the combustion pressure is allowed to work upon the under surface of the piston 100, the area thereof added to the area of the pressure area of the under surface of the valve member 118 is more than enough to overcome the bias of the spring 144. To minimize the forces tending to resist opening of the valve member 118, the spring 107 for the piston 100 is made relatively weak, being sufficient merely to bias the plunger to the position shown in Fig. 2.

Assuming that the engine pistons 12, 14, are about at their innermost positions (starting position), as shown in Fig. 1, a supply of fuel-air mixture under pressure is injected into the combustion space S. Upon reaching a pressure of approximately 100 p.s.i. the mixture will cause the lowering of the plunger 156 against the bias of the spring 172 closing the switch 174. Closing of this switch will cause sparking of the spark plug 188 and ignition of the fuel mixture will take place. The amount of fuel mixture, the initial pressure and temperature thereof, and the size of the housing 74 is such as to produce approximately 500 p.s.i. of combustion pressure so that the expansion work of the ignited compressed fuel-air mixture trapped in the combustion chamber potentially just covers a full outward stroke of the engine pistons 12, 14, performing the diesel compression of the counter cylinder, the suction work of the corresponding compressor cylinders, the air displacement of the compressor cylinders of the starting side, the work absorbed by the injection system, the control system, the lubrication system and to cover all mechanical losses during the stroke.

Upon reaching the peak combustion pressure, which will be quite sudden, the combustion pressure will actuate the slide valve member 198 into a lower position permitting the introduction of this high pressure into the chamber 194 by way of the passageway 208, through the passage 213 and into the chamber 98 below the piston 100 for actuating the same upward thereby permitting engagement of the rod 102 with the valve stem 106. As previously stated, the peak combustion pressure in the space S is insufficient to open the valve member 118. However, with the added pressure surface area of the piston 100, the valve member 118 will open by the combined operative movement of the rod 102 upon the stem 106 and the pressure build-up on the under side of the valve member 118. It will be appreciated that the opening of the valve member 118 by the aforesaid operation is quite sudden and will occur almost instantly after the fuel mixture has been ignited. In effect, the valve opens with a snap action for permitting an almost instantaneous introduction of the pressure build-up into the engine cylinder 10. With the valve member 118 in the open position, the pressure in the chamber 74 will be admitted

5 past the valve seat 120 and into the engine chamber 10 with such suddenness that the engine pistons 12, 14 are driven outwardly in a manner similar to the normal operation of the engine, and normal operation will commence.

10 The pressure being thus released, the valve member 198 can return to its inoperative position as shown in Fig. 2. In moving to this position, the burned mixture in the chamber 98 below piston 100 will vent to atmosphere through the passageway 213, bore 209, groove 210 and the passageway 212. Upon this occurrence, the piston 100 will be forced downwardly under the bias of the spring 107 for causing closing of the valve member 118 and preventing the escape of the pressure build-up 15 in the cylinder 10 during the return compression stroke of the pistons 12, 14.

20 It will be noted that the upper surface of the land 202 and the needle valve 200 of the slide valve member 198 present a differential of areas exposed to the combustion pressure, that is, the needle valve has in effect a relatively small area subjected to the pressure when closed and therefore the full combustion pressure of 500 p.s.i. would be required in order to move the valve member 198, while once in the open position, the area of the land 202 in 25 addition to the full area of the needle valve 200 will present a relatively large area to the pressure. It will therefore be apparent that the pressure in the space S may decrease considerably, as is the case when the valve 118 is opened, without effecting the movement of the valve member 198. In fact, the area of the elements 200, 202 are so chosen that the valve member 198 remains in the lowered position, and consequently the valve member 118 30 in the open position, until the pressure within the space S has reached a value equal to the pressure at the exhaust ports of the cylinder 10. In the meantime when the pressure released from the space S falls below 100 p.s.i. the plunger 156 will move upwardly under the bias of the spring 172 in order to open the circuit to the spark plug 188. The apparatus is now in condition for another 35 starting operation in the event the need arises.

40 Although only one embodiment of the invention has been illustrated and described, it will be understood that this is shown for purposes of illustration, and that the invention may be modified and embodied in various other 45 forms without departing from its spirit or the scope of the appended claims.

What I claim is:

1. An engine starter system comprising a housing defining a combustion chamber, means for connecting said chamber to a source of fuel-air mixture, ignition means for igniting said mixture to produce a predetermined pressure in said chamber resulting from the combustion of said mixture, valve means for controlling the flow of burned fuel mixture from said chamber and having an area subjected to said predetermined pressure, means for biasing said valve means to a closed position against the force of said predetermined pressure, said housing having a cylinder-piston mechanism movable into engagement with a portion of said valve means, and means responsive to said predetermined pressure for controlling the introduction of said pressure into said cylinder-piston mechanism for actuating said valve means to an open position.

2. An engine starter system comprising a housing defining a combustion chamber, means for connecting said chamber to a source of fuel-air mixture, ignition means for igniting said mixture to produce a predetermined pressure in said chamber resulting from the combustion of said mixture, valve means for controlling the flow of burned fuel mixture from said chamber and having an area subjected to said predetermined pressure, means for biasing said valve means to a closed position against the force of said predetermined pressure, said housing having a cylinder-piston mechanism movable into engagement 60 with a portion of said valve means, and second valve

means normally biased to a closed position being responsive to said predetermined pressure for controlling the introduction of said pressure into said cylinder-piston mechanism for actuating said first valve means to an open position.

3. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means having a first means responsive to the pressure existing in said chamber whereby said valve means is urged towards said open position as said chamber pressure increases, said biasing means exerting a force upon said valve means of sufficient magnitude to prevent opening of said valve means when said first means is so urged, and second means engaging said valve means in response to increased pressure in said chamber to apply an additional force to said valve means which is of sufficient magnitude in conjunction with the effect of said first means to overcome the bias of said biasing means and move said valve to said open position.

4. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, and means engaging said valve means in response to increased pressure in said chamber to provide an additional force on said valve means of sufficient magnitude in conjunction with the force of said high pressure exerted on said area of said valve to overcome the bias of said biasing means and move said valve to said open position.

5. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, and auxiliary means movable into engagement with a portion of said valve means in response to increased pressure in said chamber to provide an additional force on said valve means which is of sufficient magnitude in conjunction with the force of said high pressure exerted on said area of said valve to overcome the bias of said biasing means and move said valve to said open position.

6. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means to said closed position, said valve means when closed having an area subjected to the pressure existing in said chamber whereby said valve means is urged towards said open position as said chamber pressure increases, said biasing means exerting a force upon said valve means of sufficient magnitude to require a pressure exerted on said area

of said valve substantially higher than said high pressure in order to obtain opening of said valve means, and means engaging said valve means in response to increased pressure in said chamber to provide an additional force on said valve means of sufficient magnitude in conjunction with the force of said high pressure exerted on said area of said valve to overcome the bias of said biasing means and move said valve to said open position.

7. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, said housing having auxiliary means therein which is movable into engagement with said valve means, and control means connected to said chamber and said auxiliary means which control means is responsive to increased pressure in said chamber to permit said high pressure medium to cause such movement of said auxiliary means whereby an additional force is applied to said valve means which is of sufficient magnitude in conjunction with the force of said high pressure exerted on said area of said valve to overcome the bias of said biasing means and move said valve to said open position.

8. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, said housing having a piston located therein which is movable into engagement with a portion of said valve means remote from said area thereof, a passageway connected to said chamber and said piston, control means in said passageway responsive to increased pressure in said chamber to permit said high pressure medium to act upon said piston and cause movement of said piston to apply an additional force to said valve means which is of sufficient magnitude in conjunction with the force of said high pressure medium exerted on said area of said valve to overcome the bias of said biasing means and move said valve to said open position.

9. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, said housing having a piston located therein which is movable into engagement with a portion of said valve means remote from said area thereof, a passageway connected to said chamber and said piston, control means in said passageway responsive to increased pressure in said chamber to permit said high

pressure medium to act upon said piston and cause movement of said piston in one direction to apply an additional force to said valve means which is of sufficient magnitude in conjunction with the force of said high pressure exerted on said area of said valve to overcome the bias of said biasing means and move said valve to said open position, and means engaging said housing and said piston for biasing said piston in a direction opposite said one direction.

10. An engine starter system comprising, a housing having a chamber therein, means connected to said chamber for rapidly creating a high pressure in a medium therein, valve means movable between open and closed positions for controlling the flow of high pressure medium from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, said housing having a piston located therein which is movable into engagement with a portion of said valve means remote from said area thereof, a passageway connected to said chamber and said piston, control means in said passageway responsive to increased pressure in said chamber to permit said high pressure medium to act upon said piston and cause such movement of said piston to apply an additional force to said valve means which is of sufficient magnitude in conjunction with the force of said high pressure exerted on said area of said valve to overcome the bias of said biasing means and move said valve to said open position and means for biasing said control means so that the portion of said passageway adjacent said chamber is closed until said high pressure is achieved in said chamber.

11. An engine starter system comprising, a housing having a chamber therein, means connected to said chamber for rapidly creating a high pressure in a medium therein, valve means movable between open and closed positions for controlling the flow of high pressure medium

5 from said chamber, means for biasing said valve means into said closed position, said valve means when closed having an area subjected to the pressure existing in said chamber whereby said valve means is urged towards said open position as said chamber pressure increases, said biasing means exerting a force upon said valve means of sufficient magnitude to prevent opening of said valve means when said high pressure exists in said chamber, said housing having a piston located therein which is movable into engagement with a portion of said valve means remote from said area thereof, a passageway connected to said chamber and said piston and control means in said passageway responsive to increased pressure in said chamber to permit said high pressure medium to act upon said piston and cause such movement of said piston to apply an additional force to said valve means which is of sufficient magnitude in conjunction with the force of said high pressure exerted on said area of said valve to overcome the bias of said biasing means and move said valve to said open position, and means for biasing said control means so that the portion of said passageway adjacent said chamber is closed until said high pressure exists in said chamber, and said control means having integral means whereby a higher pressure is required in said chamber to permit said medium to act upon said piston than is required to cause said last mentioned biasing means to move said control means to close said adjacent portion of said passageway.
